Inventor

Charles John Hagstrom

United States Patent Office.

CHARLES JOHN HAGSTREEM, OF CHICAGO, ILLINOIS.

Letters Patent No. 103,324, dated May 24, 1870.

IMPROVEMENT IN STEAM-BOILER FURNACES.

The Schedule referred to in these Letters Patent and making part of the same.

To all whom it may concern:

Be it known that I, CHARLES JOHN HAGSTREEM, of Chicago, in the county of Cook and State of Illinois, have invented a Smoke-burning Fire-Box; and I do hereby declare that the following is a full and exact description thereof, which will enable those skilled in the art to make and use the same, reference being had to the accompanying drawing and letters marked thereon, making a part of this description, in which—

Figure 1 is an end elevation of the fire-box and boiler.

Figure 2, a broken elevation of the opposite end of the fire-box.

Figure 3, a longitudinal elevation of a boiler and section of the fire-box.

Figure 4, a sectional elevation of the inner part of the door to the fire-box.

Figure 5, an end elevation of the door.

Figure 6, a transverse central section of the door.

Figure 7, a sectional elevation of the front of the door.

The object of the present invention is to provide more efficient means for burning the smoke in fire-boxes of boilers; and

Its nature consists in the novel construction and arrangement of devices, by means of which steam and air enter the fire-chamber, and are controlled in their action upon the flame and smoke, as the whole is hereinafter fully described.

A represents an ordinary boiler,

B, a steam-chamber;

B', a smoke-stack;

D, a spark-catcher; and

C, a fire-box; all being combined in the usual manner.

Communicating with the steam-chamber B and smoke-stack B' is a pipe, E H I, which is provided with a stop-cock F and a stop-cock J, the former cock being used to prevent steam from entering the smoke-stack, and the latter to prevent steam from entering the fire-box by means of a pipe, G, communicating with the pipe E H I.

This pipe G is so formed as to run parallel with a sliding gate, P, as shown in figs. 2 and 3, and it is provided with curved pipes, K, which conduct steam into holes, l, made in the rear and bottom part of the fire-box C, as shown more clearly in fig. 2.

In order to secure a suitable draught for the fire-box when steam is entering it, I construct a novel door, figs. 1, 3, 4, 5, 6, 7. This door is formed of two shell-castings, X h, the shell h being made so much smaller than the shell X that it will shut into the fire-box, while the shell X will shut against the outside of it.

Between these two shell parts I place a partition, g, figs. 6, 7, which has an opening, e, through, to admit air into the fire-box, said partition being provided with a sliding door, c, to close the opening e when required.

To prevent an outward blast through the opening e, the shell part h of the door is provided with small openings, b, near its end parts, by means of which and the partition g the current is mostly or entirely broken.

If, however, there should be a strong blast, the outer shell part X, having its openings Y Y made near its under side, will effectually stop sparks, and put any fire there may be in them out.

The two parts of the door may be fastened together by bolts and nuts, or by any other means which will readily permit the inner part to be removed when it is burned out, and replaced by a new casting.

The door is hinged to the front of the box C at W W, fig. 1, and to it, by means of a link, V, is attached a lever, T; whose central part is pivoted to the fire-box C, as shown at figs. 1 and 3.

The lower end of this lever is jointed to a crank, U, which is fastened to a rod, N having bearings, R R, which project downward from the bottom of the fire-box.

The opposite end of the rod N is provided with a crank, O, which is pivoted to the sliding gate P, figs. 2 and 3, the end S of the crank O being so slotted out that it will not bind on its pivot when the gate P is opened and closed.

This arrangement is such that, when the gate X h is opened, the holes l will be closed by said gate P, and vice versa, this arrangement being necessary to prevent steam from blowing smoke and fire out at the door when open.

I do not intend to use but a little steam, and for that reason make the holes in the pipes K only about one-eighth of an inch in diameter for an ordinary-sized fire-box.

The process of burning the smoke consists in driving it back toward the front of the fire-box by a damp substance, which will so incorporate itself with the smoke that the latter will be held in the fire-box long enough to be reburned, at the same time providing the fire-box with the requisite air to produce, as nearly as possible, perfect combustion.

In addition to this, the construction is such that there is an active agitation of the air and steam inside of the fire-box, which does not materially interfere with the draught through the flues.

Having thus described my invention,

What I claim, and desire to secure by Letters Patent of the United States, is—

1. The door X h, constructed in two parts, provided with openings b Y, a partition, g, and sliding door c, as and for the purpose set forth.

2. The door X h, in combination with the lever T, cranks U O, rod N, and gate P, as described.

3. The curved steam-pipes K, in combination with the pipe G E H I, and gate P, as set forth.

CHARLES JOHN HAGSTREEM.
